[57] CLAIM

The ornamental design for a combined sink strainer and scraper, as shown and described.

DESCRIPTION

FIG. 1 is a top plan view of a combined sink strainer and scraper showing our new design;

FIG. 2 is a side elevational view thereof, the opposite side being a mirror image, shown partially for clarity of illustration; and,

FIG. 3 is a bottom plan view thereof.

FIG. 1

FIG. 2

FIG. 3
